Attorney

UNITED STATES PATENT OFFICE

CHARLES THOMAS, OF BROOKLYN, NEW YORK

HAIR-WAVING DEVICE

Application filed July 26, 1929. Serial No. 381,252.

This invention relates to improvements in hair waving devices, and has particular reference to a permanent waving curling stick.

The primary object of the invention resides in a hair waving device resembling a curling iron in which the jaw ends removably support curling sticks to receive the hair to be waved which is wound thereon, whereby to allow withdrawal of the jaws of the iron to 10 allow curling sticks to remain in the hair with the curled hair wound thereon, after which the heat is applied in the usual manner by the permanent hair waving machine to produce the permanent wave.

15 Another object of the invention is to provide a hair winding stick for facilitating the rapid and easy winding of the hair thereon when preparing the same for waving.

A further object of the invention is the 20 provision of a hair waving device which is simple in construction, inexpensive of manufacture, and easy of operation.

With these and other objects in view, the invention resides in the combination and arrangement of parts, the essential features of 25 which will be hereinafter fully described and which are shown in the accompanying drawings, in which:

Figure 1 is a side elevational view of my 30 improved hair waving device.

Figure 2 is an enlarged vertical longitudinal sectional view through the jaw ends of the device showing the same in a closed position, the dotted lines indicating the position 35 of the curling stick when removed from the supporting jaws.

Figure 3 is an enlarged vertical transverse sectional view on the line 3—3 of Figure 2.

Figure 4 is a perspective view showing 40 my improved hair waving device in use.

Figure 5 is a sectional elevational view of a modified form of curling stick.

Figure 6 is a similar view of another modification.

45 Figure 7 is a similar view of a still further modification.

Referring to the drawing by reference characters the numeral 10 designates my improved hair waving device in its entirety, 50 which includes a pair of coacting members

11 and 12 which are pivotally connected together intermediate their ends as at 13. The members 11 and 12 embody manipulating handle portions 14 and 15 respectively on one side of their pivotal connection, and 55 clamping jaws 16 and 17, respectively on the opposite side of their pivotal action. From the description thus far it will be noted that the device resembles an ordinary curling iron in which manipulation of the handle members 14 and 15 will impart opening and closing of the respective jaws 16 and 17.

The jaw 16 is substantially crescent shaped in cross section as shown in Figure 3 of the drawing, and is reduced as at 18 to telescopically receive a tubular curling stick 19 of a similar shape. The jaws 17 unlike the jaw 16 is round in cross section, the outer end of which is reduced as at 20 to telescopically receive a similar shaped tubular curling stick 21. The shoulders formed by reducing the outer ends of the jaws act as stops for limiting insertion of the respective curling sticks thereon, and when in position upon the jaws, the said sticks are flush therewith. By constructing one of the jaws and curling sticks in the shape shown, that is round in cross section, the concavity provided in the crescent shaped stick will coat therewith to tightly grip the hair wound or entwined thereon as shown in Figure 4 of the drawings. In use a hank of hair is wound or entwined upon the curling stick and the device turned so as to bring the curling stick close to the scalp as shown in Figure 4, after which the jaws of the pivotally connected members are withdrawn from the respective curling sticks, leaving only the curling sticks upon the head of the person receiving the wave. The hair is now prepared for receiving the permanent waving machine by which heat is applied in order to set the wave. After the wave has been formed, the curling sticks are removed and may be used over and over again in connection with the holder implement.

In Figure 5 of the drawing I have shown a modified form in which the numeral 22 designates a solid curling stick having a socket 23 in one end thereof which receives 100

the reduced pin or stud 24 of the holder member or jaw 25.

In Figure 6 I have shown a further modified form in which the body of the curling stick is shown at 26, one end of which is provided with a reduced stud or shank 27 split longitudinally as at 28 for insertion into the socket 29 provided in the outer end of the jaw or holder element 30. By splitting the stud 27, the same is made resilient for frictional engagement with the walls of the socket 29.

Figure 7 shows a further modification wherein the numeral 31 designates the body of the curling stick which is provided with a reduced shank 32 for insertion into a socket 33 provided in the outer end of the jaw or holder element 34. The side wall of the socket 33 is provided with an elongated slot 35 which opens at the outer end thereof for receiving a manipulating element 36 extending at right angles to the axis of the reduced shank 32. The pin or manipulating member 36 may be grasped to slide the winding stick 31 from the socket 33.

Having thus described the invention, what I claim as new and desire to secure by Letters Patent is:—

1. A hair waving device including a pair of members pivotally connected together intermediate their ends, each member embodying a handle portion at one end and a jaw at the opposite end, and winding sticks supported by the jaw ends of said members on which the hair to be waved is wound, and removable therefrom with the hair wound thereon.

2. A hair waving device including a pair of members hingedly connected together intermediate their ends, each member embodying a manipulating handle portion and a jaw, and a pair of tubular curling sticks freely telescoping the jaws of said members to receive the wound hair to be waved, and freely removable from the jaws with the hair wound thereon.

3. In a hair waving device, a pair of pivotally connected jaws, one of said jaws being round in cross section, and the other crescent shaped in cross section, and tubular winding sticks similarly shaped in cross section as the respective jaws for freely fitting thereover to receive the windings of hair to be waved, and freely removable from the jaws with the hair wound thereon.

In testimony whereof I affix my signature.

CHARLES THOMAS.
